UNITED STATES PATENT OFFICE.

ROBERT S. TAYLOR, OF SEATTLE, WASHINGTON.

DESIGN FOR A SPRING-HANGER BRACKET.

59,792.

Specification for Design.

Patented Nov. 22, 1921.

Application filed June 6, 1921. Serial No. 475,443. Term of patent 7 years.

To all whom it may concern:

Be it known that I, ROBERT S. TAYLOR, a citizen of the United States, residing in the city of Seattle, in the county of King and State of Washington, have invented a new, original, and ornamental Design for a Spring-Hanger Bracket, of which the following is a specification, reference being had to the accompanying drawings, forming a part thereof.

Figure 1 of the drawings is a perspective view in front and side elevation of a spring hanger bracket for automobile springs embodying the features of my invention, and Fig. 2 is a view in rear elevation of the same.

I claim:

The ornamental design for a spring hanger bracket as shown.

ROBERT S. TAYLOR.
